UNITED STATES PATENT OFFICE.

MELVILLE E. WILSON, OF STAYNER, ONTARIO, CANADA.

TURBINE WINDMILL.

Application filed May 6, 1926. Serial No. 107,246.

This invention relates to improvements in windmill constructions.

The primary object of this invention is the provision of an improved type of windmill, embodying a manually operated turbine wheel, which may be conveniently and efficiently adjusted to permit of the variable closing thereof, for regulation to obtain various speeds of rotation of a driven shaft.

10 A further object of the invention is the provision of a novel windmill construction embodying a plural segmental cylindrical shaped construction, the segments of which may be relatively adjusted to provide an enclosed cylinder, or which may be laterally moved to provide vanes having various degrees of extension, to permit the drive of an operated shaft at various speeds.

Other objects and advantages of this invention will be apparent during the course of the following detailed description.

In the accompanying drawings, forming a part of this specification, and wherein similar reference characters designate corresponding parts throughout the several views,

20 Figure 1 is a side elevation of the improved windmill construction, showing the bladed construction thereof open and ready for use.

Figure 2 is a plan view of the open turbine wheel, showing the novel construction thereof.

Figure 3 is a sectional view taken substantially on the line 3—3 of Figure 2.

30 Figure 4 is a fragmentary transverse sectional view taken through the turbine wheel construction at the top of the windmill, and showing the related parts thereof, this view being taken substantially on the line 4—4 of Figure 1.

Figure 5 is a plan view of the wheel of the windmill in closed position.

Figures 6 and 7 are sectional views taken substantially on their respective lines in Figures 1 and 3 of the drawings.

In the drawings, wherein for the purpose of illustration is shown only a preferred embodiment of this invention, the letter A may generally designate the windmill, which may comprise a supporting tower or derrick B, rotatably supporting a vertical shaft C therein, which extends upwardly to the top of the windmill, and whereon a novel wheel, D of an adjustable turbine type, is positioned, the same having means E to operate the

same from the ground at the base of the tower B.

The tower B is of course of any approved construction, and may comprise the longitudinal corner members 10, slightly inclined to the vertical, which are spread at the base 11 of the derrick or tower, and which at the upper ends thereof are attached at 12, in any approved relation; suitable cross braces 13 being provided to connect the longitudinal members 10, as well as diagonal reinforcing braces 14 being used for such purpose.

The shaft C extends vertically thru the tower or derrick B, and at its lower end the same may be provided with any suitable gearing for operating a pump, generator, dynamo, or the like. At its upper end 20 the shaft C extends above the connecting cap 12 of the tower B, and thereon the wheel construction D is mounted, above the top of the tower B, as is conventional formation, but in a manner which is distinctly novel.

The wheel construction D preferably comprises a pair of hollow half cylindrical sections 24 and 25, which are complementary in providing a hollow cylinder, as shown in Figure 5 of the drawings. These half or cylindrical sections 24 and 25 each include top and bottom flat walls 26 and 27 respectively, connected by means of curved angle irons 28 to the upper and lower margins of a 180° curved wall 29. The half cylinder segments 24 and 25 have pockets 34 and 35 opening at the chord or flat facing sides thereof, so that as the segments 24 and 25 are slid away from each other in opposite directions, the pockets thereof are opened outwardly, one facing forwardly and the other facing rearwardly, in order that the same may take the wind in the same relation, as is readily apparent from Figure 6 of the drawings.

At the top and bottom straight edges of the half cylinder sections 24 and 25, at the open side of the pocket of each section, supporting angles 38 are provided, having the inwardly extending flanges 39, thereon, which extend into obstructing relation across the adjacent ends of the pockets of the said half cylinder sections, for sliding engagement with upper and lower supporting channels 40 and 41 which are mounted upon the shaft 20.

The channel 40 is mounted at the extreme

top of the shaft 20, with the channel groove 43 thereof facing upwardly; the top of the shaft 20 being secured by means of a flanged attaching ring 45 with the base of the channel 40, at a point midway between the ends of the channel 40, so that the legs 47 of the channel face upwardly, to receive the flanges 39 of the segments 24 and 25 in a hooked engagement over said legs 47 of the top channel 40, as is readily apparent from Figure 4 of the drawings. In similar manner the lower channel 41 is connected midway between its ends by means of a ring-shaped attaching flange 48 which is secured on the shaft 20 in a keyed relation thereon; the shaft 20 of course extending thru the base of the flange 41, as illustrated in Figure 4, so that the legs 50 of the said channel 41 face downwardly, and at the inner sides of which the flanges 39 of the lower angles 38 of said half sections 24 and 25 are hooked in a sliding relation in the passageway of the channel 41.

Incident to the above connection of the half cylinder sections 24 and 25 upon the upper and lower channels 40 and 41, it is readily apparent that said half sections 24 and 25 may be slid along the channels 40 and 41, to position them in a true cylinder forming relation, or in laterally extended relation to open the pockets 34 and 35 of said cylinder segments 24 and 25, as is apparent from Figures 1 and 2 of the drawings. Of course, the channels 40 and 41 are greater in length than the diameter of the cylinder which is formed by the sections 24 and 25, as is apparent from Figure 5 of the drawings.

Upper and lower expansion springs 55 and 56 are provided for normally urging the half cylinder sections 24 and 25 into an open extended relation to expose the pockets thereof. These springs 55 and 56 are preferably of the ordinary spiral type, and at their ends they are connected by means of eye bolts or analogous expedients to the opposite ends of the sections 24 and 25, that is, one end of each spring is connected to one corner at the open pocket side of the one segment, and the same spring at its opposite end is connected to a diametrically opposed corner at the open pocket side of the other segment, so that incident to the inherent tendency of the springs, the sections 24 and 25 will be forced in opposite directions along their supporting channels, to expose the open pocketed sides thereof, as illustrated in Figure 2 of the drawings.

Referring to the means E by which the half cylinder sections 24 and 25 may be closed into a cylinder forming relation, or by means of which they may be opened to various degrees, to permit of the shaft C to be driven at various speeds, it is preferred to provide a collar 60 in a splined relation

upon the shaft C, at the end 20 between the upper and lower supporting channels 40 and 41; this collar 60 having a narrow transverse portion 61 extending at opposite sides of the axis of the shaft 20; and the portion 61 at one end being pivotally connected to a connecting link 62 and at its opposite end being pivotally connected to a connecting link 63, preferably by means of eye bolts. The connecting links 62 and 63 are of course disposed at opposite sides of the shaft C, and they are respectively connected by means of eye bolts to the diametrically opposed sides of the half cylinder sections 24 and 25, preferably immediately beneath the channel 40. It is thus readily apparent that if the collar 60 is slid downwardly upon the shaft end 20, incident to the connection of the half sections 24 and 25 thereto, by means of the links 62 and 63, the said half sections or cylindrical sections 24 and 25 will be moved towards each other into a cylindrical formation, as illustrated in Figure 5.

An annular ring 67 is supported immediately at the top of the cap 12, beneath the lower wind wheel supporting channel 41, the same including a ring-shaped base 68 and an upstanding attaching flange 69; said annular ring 67 being supported for rotation with the shaft 20, by means of vertical rods 70 and 71, which are connected in the base 68 thereof, as illustrated in Figure 3 of the drawings, and at their upper ends being connected in the portion 61 of the splined collar 60, at opposite sides of the shaft end 20.

The flange 69 forms a track, upon which diametrically opposed rollers 75 and 76 bear; the rollers having suitable depending link rod connections 77 and 78 respectively, which at their lower ends are connected to a transverse member 80 which has a cable 81 connected at its upper end thereto, and depending axially within the tower B, alongside of the shaft C, to any convenient operating mechanism, which the operator may move in order to draw the cable 81 downwardly, and thus thru the member 80; the rods 77 and 78; ring 67; and rods 70 and 71 move the collar 60 downwardly for closing the half cylindrical sections 24 and 25 to the proper degree.

From Figure 4 of the drawings it is apparent that the shaft C has a thrust bearing on the top 12 of the tower B, illustrated at 85, and which may be of any approved construction in order to sustain the weight and thrust of the wheel D.

From the foregoing description of this invention it is apparent that a novel type of turbine windmill has been provided, the wheel of which is of novel character, which may be efficiently operated to close the same, or extend the same to various degrees, in order that the shaft may be operated at vari-

ous speeds. The parts are simple in construction, and efficiently arranged.

Various changes in the shape, size, and arrangement of parts may be made to the form of invention herein shown and described, without departing from the spirit of this invention or the scope of the claims.

I claim:

1. In a windmill construction the combination of a supporting frame, a shaft rotatably supported by the frame, a cylindrical shaped wind wheel for the shaft keyed thereto for rotation therewith, and including complementary sections with means to slidably mount the same for slidable movement in parallel planes whereby the same may be collapsed or laterally slid in offset relation to vary the effective wind surfaces thereof.
2. As an article of manufacture a wheel for windmills comprising a supporting frame, and half cylindrically formed hollow sections having pockets therein open at the chord side thereof, said sections being slidably mounted on the frame in facing relation at the open sides of said pockets to permit the same to be moved together to form a closed hollow cylinder, or laterally slid in offset relation to expose various widths of the pockets thereof for effective wind reception.
3. As an article of manufacture a wheel construction for windmills comprising a shaft, upper and lower channels supported in spaced parallel relation by the shaft having respectively upper and lower spaced legs defining the channel grooves, half cylindrical shaped hollow sections having pockets therein, said pockets being open at a side of each of the said sections, retaining flange means supported at the open sides at the top and bottom of each of said sections in engagement over the legs of said channels for slidably mounting said sections on said channels with the pockets in facing relation, said channels being sufficiently long to permit the half cylindrical shaped sections to be slid therealong into an offset relation to expose various widths of the pockets thereof, and means to move said half sections into pocket facing relation to form a cylinder of said half sections, with the pockets thereof closed to entrance of wind.
4. As an article of manufacture a wheel construction for windmills comprising a shaft, upper and lower channels supported in spaced parallel relation by the shaft having respectively upper and lower spaced legs defining the channel grooves, half cylindrical shaped hollow sections having pockets therein, said pockets being open at a side of each of the said half sections, retaining flange means supported at the open sides of the top and bottom of each of said sections in engagement over the legs of said channels for slidably mounting said sections on said

channels with the pockets in facing relation, said channels being sufficiently long to permit the half cylindrical shaped sections to be slid therealong into an offset relation to expose various widths of the pockets thereof, means to move said half sections into pocket facing relation to form a cylinder of said half sections, with the pockets thereof closed to entrance of wind, and spring means connecting said sections together and normally urging them into an offset pocket open relation.

5. In a windmill the combination of a supporting tower, a shaft rotatably supported by the tower having an end extending upwardly therefrom, channel means supported by the shaft transversely at the upper end of said shaft, and half cylindrical segments slidably mounted on said channel means, said segments being hollow and having open pockets therein.

6. In a windmill the combination of a supporting tower, a shaft rotatably supported by the tower having an end extending upwardly therefrom, channel means supported by the shaft transversely at the upper end of said shaft, half cylindrical sections slidably mounted on said channel means, said sections being hollow and having open pockets therein, and means for moving said half cylindrical sections along the channel means to open or close the pockets thereof for reception of wind.

7. In a windmill the combination of a supporting tower, a shaft rotatably supported by the tower having an end extending upwardly therefrom, channel means supported by the shaft transversely at the upper end of said shaft, half cylindrical sections slidably mounted on said channel means, said sections being hollow and having open pockets therein, means for moving said half cylindrical sections along the channel means to open or close the pockets thereof for reception of wind, and spring means normally urging said sections into a pocket open relation.

8. In a windmill the combination of a supporting frame, a shaft rotatably carried by the supporting frame, a transverse member rigid with the shaft at the upper end thereof, half cylindrical shaped sections slidable along said member at opposite sides thereof and at opposite sides of the shaft, said sections being hollow and having pockets therein, means to normally open the pockets, and operating means connected with said sections and extending to substantially the base of said supporting frame by means of which said sections may be relatively moved towards each other into a collapsed relation with the pockets in closed relation.

9. In a windmill construction the combination of a supporting tower, a shaft vertically supported in the supporting tower for rotation, transverse members carried in

spaced relation at the upper end of said shaft above the top of said tower, hollow half cylindrical shaped sections slidably mounted on said spaced transverse members having 5 pockets with the open sides in faced relation, spring means normally urging said sections into an offset relation to expose the pockets thereof at opposite sides of the axis of the shaft, a collar slidably mounted on said 10 shaft, links connected with said collar at opposite sides of the shaft and at their outer ends said links being connected with the said sections, a cable extending along the shaft to the base of the tower, and means 15 connecting the cable at its upper end to said collar whereby upon pulling downwardly on the cable the collar will be slid along said shaft to collapse said sections together to form a cylinder with the pockets of the 20 sections closed.

10. In a windmill construction the combination of a supporting tower, a shaft vertically supported in the supporting tower for rotation, transverse members carried in 25 spaced relation at the upper end of said

shaft above the top of said tower, hollow half cylindrical shaped sections slidably mounted on said spaced transverse members having pockets with the open sides in faced relation, spring means normally urging said sections into an offset relation to expose the pockets thereof at opposite sides of the axis of the shaft, a collar slidably mounted on said shaft, links connected with said collar at opposite sides of the shaft and at their 30 outer ends said links being connected with the said sections, a cable extending along the shaft to the base of the tower, and means connecting the cable at its upper end to 35 said collar whereby upon pulling downwardly on the cable the collar will be slid along said shaft to collapse said sections together to form a cylinder with the pockets of the sections closed, said last mentioned means including an annular track supported by the 40 collar below said sections, and roller means supported by the cable at its upper end operating on said track. 45

MELVILLE E. WILSON.
